CONTROL CONSOLE

Vincent F. Santulli, Manhasset, and John J. Gazzo,
Commack, N.Y., assignors to Porta Systems Corp.,
Roslyn, N.Y.

Filed June 1, 1972, Ser. No. 258,927

Term of patent 14 years

Int. Cl. D14—02

U.S. Cl. D26—5 C

FIG. 1

FIG. 3

FIG. 2

FIG. 4

FIG. 5

FIG. 1 is a perspective view of a control console embodying our new design;

FIG. 2 is a right side elevational view thereof;

FIG. 3 is a rear elevational view thereof;

FIG. 4 is a front view of the vertically disposed front panel thereof; and

FIG. 5 is a top view of the horizontally disposed front panel thereof.

We claim:

The ornamental design for a control console, substantially as shown.
